VELOCIPED FRAME

Bert J. Anderson, Hammond, Ind.

Application January 28, 1935, Serial No. 3,742

19 Claims. (Cl. 208—113)

This invention relates to an improvement in a sheet metal velocipede frame and has for one of its principal objects the economical production of an article of the class referred to which is rugged and sturdy and which readily lends itself to assembly with various sizes of wheels.

A further important object of this invention resides in the provision of means for extending the rear end of the floor plate member upwardly and through the backbone.

Another and still further important object of the frame of this invention resides in the provision of means for securing a seat thereto.

Still another and further important object of this invention resides in the provision of means for securing and maintaining the lower edges of the frame in spaced apart relation.

An additional object of importance resides in the fact that the lowered cost of production of the frame of this invention is due to limiting the number of operations usually found necessary in a stamped frame, and not by the substitution of lighter or cheaper material.

The invention possesses other objects and features of advantage, some of which, with the foregoing, will be set forth in the following description.

The invention, in a preferred form, is illustrated in the annexed drawing and hereinafter more fully described.

In the drawing:

Figure 1 is a side elevation of the frame of this invention.

Figure 2 is a top plan view thereof.

Figure 3 is a bottom plan view of the frame and shows the relative positions of the securing tongues and floor plate.

Figure 4 is a side elevation of the upright portion of the floor plate member.

Figure 5 is a front view of a portion of the floor plate member taken on the line 5—5 of Figure 4, looking in the direction indicated by the arrows.

Figure 6 is a sectional view taken on the line 6—6 of Figure 2.

Figure 7 is a sectional view taken on the line 7—7 of Figure 1.

Figure 8 is a sectional view taken on the line 8—8 of Figure 1.

As shown in the drawing:

The reference numeral 10 indicates in a general way the backbone of the frame of this invention, which is substantially U-shaped in cross section, which includes a head 12; outwardly and rearwardly disposed axle supporting members 14,

which are also substantially U-shaped in cross section; and step plates 16.

The entire frame is formed of a single stamping, with the head 12 drawn down to form a solid front.

The lower edges of the frame are spaced apart and portions thereof are turned inwardly to form a flat surface 22. Centrally located in the upper surface of the head 12 is a draw necked aperture 18, which is adapted to receive a steering post.

A tongue 20 formed of a portion of the backbone and extending upwardly and rearwardly therefrom forms a member for securing the front end of a saddle or other suitable seat to the frame.

Secured to portions of the lower edges of the U-shaped frame is a floor plate member 28, the forward portion 24 thereof having an upturned edge 25, adapted to contact the outer surface 20 of the head 12, and also being apertured as shown by the reference numeral 26 to receive a steering post. The central portion of the floor plate member is slightly raised and has downwardly turned edges 29 which allow this portion of the member to be secured within the frame 10 as is clearly shown in the drawing. The rear portion 30 of the floor plate member 28 extends upwardly and through the frame 10 as is best shown in Figures 1 and 2. The extreme end 32 of the portion 30 is horizontal and is adapted to receive and support the rear end of a saddle or other suitable seat.

Formed of a portion of the member 30 and extending rearwardly is a tongue 34, which is adapted to be secured to the bottom surface of the backbone 10.

The edges of the outwardly and rearwardly extending axle supporting members 14 are secured in spaced apart relation by tongues 36 which are formed of portions of the inner edge and which are secured preferably by welding to the flat surface 22.

Aligned draw necked apertures 38 adjacent the rear end of the frame are adapted to receive 45 an axle.

The step plates 16 are joined to the rear portion of the frame by webs 40. The web and step plate members being an integral part of the stamping, provide a reinforcing element 50 which prevents the ends of the axle supporting member 14 from spreading or getting out of alignment.

Apertures 42 may be provided in the floor plate member 28 to facilitate assembly.

It will be apparent from the foregoing that herein is provided a velocipede frame which, because of its construction of a single piece of sheet metal, may be economically manufactured.

5. Moreover, it is sturdy and rugged and, while being considerably lighter than the ordinary sectional frame, will wear much longer and withstand greater abuse.

I am aware that many changes may be made 10 and numerous details of construction varied throughout a wide range without departing from the principles of this invention, and I, therefore, do not purpose limiting the patent granted hereon otherwise than as necessitated by the prior art.

15. I claim as my invention:

1. A velocipede frame formed of a single stamping and consisting of head, backbone, and axle supporting portions, a drawneck steering post receiving aperture in the head portion, a tongue 20 extending upwardly and rearwardly from said backbone portion, and a transverse slot in the backbone in the rear of and in alignment with said tongue.

2. A velocipede frame formed of a single stamping and consisting of an apertured head portion, 25 a backbone portion substantially U-shaped in cross section, a tongue extending upwardly and rearwardly from said backbone portion, and a transverse slot in the backbone in the rear of and in alignment with said tongue.

3. A velocipede frame formed of a single stamping and consisting of head, backbone, and axle supporting portions, a drawneck steering post receiving aperture in the head portion, a tongue 35 extending upwardly and rearwardly from said backbone portion, and a transverse slot in the backbone in the rear of and in alignment with said tongue, said axle supporting portion terminating in three downwardly and rearwardly extending joined ends.

4. A velocipede frame formed of a single stamping and consisting of head, backbone, and axle supporting portions, a drawneck steering post receiving aperture in the head portion, a tongue 45 extending upwardly and rearwardly from said backbone portion, and a transverse slot in the backbone in the rear of and in alignment with said tongue, said axle supporting portion terminating in three downwardly and rearwardly extending joined ends, and portions forward of each of said ends being substantially U-shaped in cross section.

5. A velocipede frame formed of a single stamping and consisting of head, backbone, and axle 55 supporting portions, a drawneck steering post receiving aperture in the head portion, a tongue extending upwardly and rearwardly from said backbone portion, and a transverse slot in the backbone in the rear of and in alignment with said tongue, said axle supporting portion terminating in three downwardly and rearwardly extending joined ends, the portions forward of each of said ends being substantially U-shaped in cross section, and a plurality of tongues extending 60 across the openings of certain of said U-shaped portions.

6. A velocipede frame formed of sheet metal and having a steering post receiving aperture in one end and aligned axle receiving apertures in 70 the opposite end, said last named end being apertured and the metal of said apertures being turned to form step plates of the lower edges of said apertures.

7. A velocipede frame formed of sheet metal 75 and comprising a longitudinal central portion,

substantially U-shaped in cross section, the rear portion of said frame being apertured and terminating in a substantially three pronged end, the end of each outer prong being joined to the end of the central prong by an integral piece of the 5 frame which is turned to form a step plate on the lower edge of each aperture.

8. A velocipede frame formed of sheet metal and comprising a longitudinal central portion substantially U-shaped in cross section, portions 10 of the edges of said frame being turned inwardly, an apertured floor plate member having upwardly turned edges on the forward portion and downwardly turned edges on the central portion thereof secured to the lower edges of the frame, 15 said member having an upwardly turned rear portion, and means for securing a part of said floor plate member to the upper inside surface of the frame.

9. A velocipede frame comprising a substantially U-shaped central portion having outward and rearwardly extending members near the rear end thereof, the rear ends of said central portion and said members being spaced apart and in alignment, step plates connecting said ends, 20 an apertured floor plate member secured to the edges of said U-shaped portion, the rear end of said floor plate member being turned upwardly and rearwardly and extending through the central portion of the frame. 30

10. A velocipede frame comprising a substantially U-shaped central portion having outward and rearwardly extending U-shaped members near the rear end thereof, portions of the inner edges of said members being turned forward and 35 connected to the outer edges of said members, the rear ends of said central portion and said members being spaced apart and in alignment, step plates connecting said ends, an apertured floor plate member secured to the edges of said 40 U-shaped portion, the rear end of said floor plate member being turned upwardly and rearwardly and extending through the central portion of the frame.

11. In a velocipede frame, a floor plate member 45 having a flat apertured front portion and an upwardly and thence rearwardly turned rear portion, and a tongue located in the central part of the upright portion and protruding rearwardly. 50

12. A velocipede frame formed of a single sheet metal stamping and comprising an arched backbone portion and an apertured rear portion, one of said apertures being formed on each side of the center line of said rear portion and spaced therefrom, a portion of the stock from said apertures being turned to the horizontal plane to form step plates of the bottom edges of the apertures. 55

13. In a sheet metal velocipede frame, an apertured stamping having a curved backbone portion 60 and downwardly turned spaced apart sides, and a seat supporting member secured to the inner surface of said stamping and extending upwardly therethrough, portions of said seat supporting member being adapted to be secured parallel to 65 and adjacent each lower edge of said backbone.

14. In a sheet metal velocipede frame, an apertured stamping having a curved backbone portion and downwardly turned spaced apart sides, said aperture comprising a slot transverse the 70 longitudinal axis of said frame, and a seat supporting member secured to the upper inside surface of said stamping and extending outwardly through said slot. 75

15. In a sheet metal velocipede frame, an aper- 75

- tered stamping having a curved backbone portion and downwardly turned spaced apart sides, said aperture comprising a slot transverse the longitudinal axis of said frame, a combination seat supporting and spacing member secured to both the inside and outside surface of said stamping and one end of said member extending outwardly therethrough, and outwardly extending apertured rear portions of said frame adapted to receive and support an axle therebelow.
16. In a sheet metal velocipede frame, an apertured stamping having a curved backbone portion and downwardly turned spaced apart sides, a combination seat supporting and spacing member secured to the inner surface of said stamping and extending upwardly and outwardly through said aperture, the forward end of said combination member being turned upwardly and secured to the outer surface of the front portion of said stamping, and outwardly extending apertured rear portions of said frame adapted to receive and support an axle therebelow.
17. In a sheet metal velocipede frame, an apertured stamping having a curved backbone portion and downwardly turned spaced apart sides, a

seat supporting member secured to the inner surface of said stamping and extending outwardly through said aperture, and step plates formed of portions of the stamping on each side of the rear part of said backbone portion.

18. In a sheet metal velocipede frame, an apertured stamping having a curved backbone portion and downwardly turned spaced apart sides, a seat supporting member secured to the inner surface of said stamping and extending outwardly through said aperture, outwardly extending apertured rear portions of said frame adapted to receive and support an axle therebelow, and step plates formed of portions of the rear end of said stamping.

19. In a sheet metal velocipede frame, an apertured stamping having a curved backbone portion and downwardly turned spaced apart sides, a seat supporting member secured to the inner surface of said stamping and extending outwardly through said aperture, and portions of the stamping being turned to the horizontal plane to form step plates.

BERT J. ANDERSON.
